UNITED STATES PATENT OFFICE.

ALBERT D. HOMARD, OF MASSILLON, OHIO.

LUBRICATOR FOR FLAKED GRAPHITE.

SPECIFICATION forming part of Letters Patent No. 746,837, dated December 15, 1903.

Application filed April 28, 1902. Serial No. 104,975. (No model.)

To all whom it may concern:

Be it known that I, ALBERT D. HOMARD, a citizen of the United States, residing at Massillon, county of Stark, State of Ohio, have 5 invented a certain new and useful Improvement in Lubricators for Flaked Graphite; and I declare the following to be a full, clear, and exact description of the invention, such as will enable others skilled in the art to which 10 it pertains to make and use the same, reference being had to the accompanying drawings, which form a part of this specification.

This invention relates to lubricators, and has for its object an improved lubricator 15 adapted to employ flaked graphite or finely-ground graphite for lubricating purposes.

In a patent granted to me September 29, 1896, No. 568,616, is described a lubricator intended to be employed for the purpose of dispensing 20 flaked graphite. I have found in using the lubricator therein described that a difficulty occurred because of the liability of the steam that passes into the lubricator to exert pressure on the piston-valve to become loaded 25 with powder of the graphite that passes down in proximity to and at times through the steam and to deposit the graphite in the passages to the lubricator, thereby clogging the valves and the passages. By the improve- 30 ment hereinafter described this difficulty is overcome.

In the drawings, Figure 1 is a vertical cross-section of the lubricator. Fig. 2 is an enlarged detail of the check-valve in the steam- 35 passage.

In the present case the lubricator is shown connected to a chest-plug of a locomotive-cylinder.

A indicates the reservoir in which the powdered graphite is contained. The powdered graphite is fed from this reservoir by a stationary feed-tube B, that is secured to the bottom of the reservoir and leads upward to near the top thereof. Preferably, but not necessarily, the tube leads through a piston D, which presses upward against the powdered graphite supported above it. The powdered graphite feeds outward through a pas-

sage 2 in the coupling 3, past a hand-actuated valve 4, and past a check-valve 5, which 50 seats upward and is near the mouth of the tube 2, where it leads into the chest-coupling 6, by which the device is coupled to the engine or to the steam-chest. The check-valve 5 is pressed upward against its seat by a coil-spring 7, held in place by a perforated nut 8. The piston D is driven upward by steam that enters the chamber α through steam-passage 9, into which the steam enters by a passage through pointed nozzle 10, that projects into 60 the chamber within the coupling 6. The nozzle 10 is provided with a check-valve 11, which is opened upwardly by the force of the steam. A hand-valve 12 is arranged to regulate the admission of steam through the passage 9 65 into the chamber α .

The ordinary coupling for the oil-lubricator which employs the tallow-pipe 13 and admits oil into the engine by the perforated check-valve 14 leads into the coupling 6, 70 which is utilized for both the dry lubricant and the oil lubricant.

What I claim is—

1. In an automatic feeder for powdered graphite, a cylinder, a piston therein, said cylinder being provided with a chamber on one side of said piston adapted to contain powdered graphite, a feed-passage for said graphite leading from said chamber into a chamber containing a variable steam-pressure, an induction-passage for steam opening into said cylinder upon the opposite side of the piston to the graphite-chamber and a nozzle surrounding the end of the steam-passage projecting into the variable steam-pressure 80 chamber from an upper wall of said chamber.

2. In an automatic feeder for powdered graphite, a cylinder, a piston therein, said cylinder being provided with a chamber on one side of said piston adapted to contain 90 powdered graphite, a feed-passage for said graphite leading from said chamber into a chamber containing a variable steam-pressure, an induction-passage for steam opening into said cylinder upon the opposite side of the piston to the graphite-chamber and a noz- 95

zle surrounding the end of the steam-passage
projecting into the variable steam-pressure
chamber from an upper wall of said chamber,
a check-valve in the steam-passage opening
5 toward the cylinder, and a check-valve in the
graphite-passage opening toward the variable
steam-pressure chamber.

In testimony whereof I sign this specifica-
tion in the presence of two witnesses.

ALBERT D. HOMARD.
